(57) **CLAIM**

The ornamental design for a hamburger grill basket, as shown and described.

DESCRIPTION

FIG. 1 is a top perspective view of a hamburger grill basket showing my new design;

FIG. 2 is a left side elevation view thereof, the right side being a mirror image;

FIG. 3 is a front end elevation view thereof;

FIG. 4 is a rear end elevation view thereof;

FIG. 5 is a top plan view thereof;

FIG. 6 is a bottom plan view thereof; and,

FIG. 7 is an exploded perspective view thereof.

The broken line representation of a handle, handle rods and clasp shown in FIGS. 1-7 are for illustrative purposes only and form no part of my claimed design.
